HIS ATTORNEY

UNITED STATES PATENT OFFICE

109,274

DESIGN FOR A COCKTAIL NAPKIN

Frederick R. Helms, Swansea, Mass.

Application February 5, 1938, Serial No. 74,915

Term of patent 3½ years

To all whom it may concern:

Be it known that I, Frederick R. Helms, a citizen of the United States, residing at Wilbur Avenue, in the city of Swansea, county of Bristol, and State of Massachusetts, have invented a new, original, and ornamental Design for a Cocktail Napkin, as shown in the accompanying drawing, the single figure of which shows a cocktail napkin embodying my design.

I claim:

The ornamental design for a cocktail napkin, as shown.

FREDERICK R. HELMS.
